ATTORNEY

UNITED STATES PATENT OFFICE.

DE WANE B. SMITH, OF DEERFIELD, NEW YORK.

DESIGN FOR A SPRAYER-BODY.

SPECIFICATION forming part of Design No. 29,625, dated November 8, 1898.

Application filed October 17, 1898. Serial No. 693,843. Term of patent 34 years.

To all whom it may concern:

Be it known that I, DE WANE B. SMITH, a citizen of the United States, and a resident of Deerfield, in the county of Oneida and State of New York, have invented and produced a new and original Design for Sprayer-Bodies, of which the following is a specification, reference being had to the accompanying drawings, forming a part thereof.

Figure 1 shows a perspective view of my design of sprayer-body. Fig. 2 shows a perspective view of my design of sprayer-body from another point of view.

The leading features of my design are the form or configuration of the sprayer-body, as shown, and consisting of the cylindrical portion 1 and the triangular portion 2, arranged

at one end and crosswise with reference to the part 1, one edge of the portion 2 converging with and meeting one end of the portion 1 ²⁰ and the other edge of the portion 2 being suspended from the middle portion of the part 1 by a connecting strap or piece 3.

What I claim as new, and desire to secure by Letters Patent, is—

The design for a sprayer-body, as herein shown and described.

In witness whereof I have hereunto set my hand, in the presence of two witnesses, this 7th day of October, 1898.

DE WANE B. SMITH. ²⁵
